UNITED STATES PATENT OFFICE

ALEXANDER A. S. STUART, OF RIDGEFIELD PARK, NEW JERSEY

SURGICAL KNIFE

Application filed May 31, 1930. Serial No. 458,019.

This invention relates to surgical knives having detachable blades. Important objects of the invention are, to provide such a knife of improved and simplified design, and to provide a knife designed to facilitate the attachment and detachment of its blade.

In the drawings, Fig. 1 is a side elevation of the knife;

Fig. 2 an edge view of the knife;

Fig. 3 an enlarged side view, partly in section, showing the mounting of the blade shank in the handle socket;

Fig. 4 a view similar to Fig. 3 showing the knife blade in a reversed position;

Fig. 5 a view similar to Fig. 3 showing the blade shank partly inserted into the socket; and

Fig. 6 a transverse section taken on the line 6—6 of Fig. 3.

The knife structure includes a handle 1 and a blade 2. The handle is straight, thin and substantially flat and is preferably formed of one piece of suitable metal. At one end it is hollowed out to form a longitudinal socket 3 which defines a straight, flat, inwardly extending passage 4 terminating in a flat, circular, milled out cavity 5. Said cavity is centered with relation to the passage 4 and its diameter is greater than the width of the latter so that two forwardly converging, concave locking shoulders 6 are formed at opposite edges of the socket. An elongated, substantially V-shaped cleft 7 is formed in the socket end of the handle and extends straight inward. This cleft is cut transversely to the plane of the blade and extends through the sides of the handle at opposite sides of the socket. Its inner end terminates near the center of the cavity 5 and is rounded. At the opposite edges of the socket entrance the handle is formed with outwardly beveled or flared shoulders 8.

The knife blade 2 has an integral shank 9 and is preferably formed of thin sheet metal stock. For most of its length the shank is bifurcated by forming a straight, longitudinal slot 10 running centrally through the shank and having an enlarged rounded end 11. Said slot divides the shank into two

spring fingers 12 and 13. Finger 12 has a

straight longitudinal edge and is outwardly rounded at its free end. The outer longitudinal edge of finger 13 is straight for a portion of its length, rearward from the blade, and then curves to define a rounded locking head 14 at the end of the finger and a reduced neck portion joining said locking head to the straight portion of the finger. In contour, the rounded edge of said locking head projects transversely slightly beyond the outer straight edge of the finger and forms a forwardly directed camming surface and a rearwardly directed camming surface. At the juncture of the shank with the body of the blade the latter is widened slightly and formed with inclined stop shoulders 15 for abutting the shoulders 8 of the handle.

The spring fingers 12 and 13 of the blade shank, when free, are expanded slightly so that the width of the shank is slightly greater than that of the socket. In sliding the shank into the socket the spring fingers are compressed slightly by forcing their rounded ends against the flaring shoulders 8 at the socket entrance. When the shank is inserted far enough to bring the blade shoulders 15 against the shoulders 8 the locking head 14 enters clearance cavity 5 and snaps into locking engagement with one of the concave locking shoulders 6. The expanding tendency of the spring fingers is only partly relieved by the snapping of the locking head into locking position. Therefore the fingers will continue to press firmly against the opposite walls of the socket. There is also a snug fit between the flat opposite side faces of the shank and the flat side walls of the socket which combined with the expanding tendency of the spring fingers and the abutment of the shoulders 8 and 15 causes the blade to be firmly held against wobbling in any direction. Slot 10 extends inward to a point adjacent the shoulders 15 so that the blade shank is compressible and resilient for substantially its entire length, for good holding engagement with the handle socket.

The handle cleft 7 and the slot 10 of the inserted blade are in register and in order to remove the blade it is only required to insert a convenient tool into the slot and forcibly

withdraw the shank from the socket, the rounded locking head being cammed over the rounded locking shoulder which it engages. Furthermore the cleft and slot render the 5 knife lighter at the juncture of the blade and the handle and give the knife a good balance.

The design of the knife provides for the reversal of the blade shank in the handle socket. This is a most desirable feature in 10 a surgical knife. The handle and its socket 2 are symmetrical about a horizontal axis and are designed for the ready attachment of the blade with its edge facing in either direction. No particular care is required on the 15 part of the surgeon or his attendant in attaching the blade. The blade shank is merely thrust forcibly into the socket and automatically locked without the necessity of registering cooperating locking means 20 upon the shank and handle. Since the socket 3 is symmetrical it provides clearance and locking engagement for the shank when the latter is inserted, as shown in Fig. 3, or when it is inserted in a transversely reversed position, as shown in Fig. 4. The locking head 25 14 is located upon the same side as the knife edge. Consequently in both positions of the knife blade pressure upon the edge of the blade tends to rock the locking head in a direction to make a more secure locking engagement. The blade is of a thin, inexpensive 30 type and it is the custom to discard such blades after a single use. My invention facilitates the removal of the blades and their 35 replacement by new ones and avoids all possibility of improper setting of the blades in the handle. The surgeon is, therefore, assured of receiving the knife with its blade properly adjusted. The knife is entirely free 40 of screws, pins and projecting parts. Its structure is extremely simple and its surfaces are smooth so that it may be easily kept clean and sanitary.

What I claim is:

45 1. A surgical knife comprising a blade integrally formed with a flat shank in the plane of the blade and longitudinally bifurcated to form two flexible and resilient fingers; a locking projection integrally 50 formed on one of said fingers at a point spaced materially from the blade and projecting transversely outward from the outer longitudinal edge of the finger and having camming surfaces at the forward and rear 55 edges thereof; a handle formed at one end with a flat shank-receiving socket defining an entrance passage of less width than the expanded shank and locking projection and laterally extended to form locking shoulders 60 extending transversely outward from the opposite longitudinal edges of said passage near the inner end thereof, the shank fingers being compressible toward each other in the plane of the shank and blade for endwise 65 insertion of the shank into the socket and ex-

pansible to snap the locking projection into yieldable locking engagement with either of said locking shoulders, the handle, shank and locking projection being formed to cooperate for the insertion and locking of the shank in transversely reversed positions and for the withdrawal of the shank by an outward pull upon the blade through an implement inserted in shank bifurcation, and the handle cross section extending outward beyond the inserted locking projection in both of its locked positions to shield the locking projection from contact with the hand of the user of the knife.

2. A surgical knife comprising a blade 80 integrally formed with a flat, transversely compressible and resilient shank in the plane of the blade; a locking projection formed upon the shank at a point spaced from the blade and projecting transversely outward from one of the outer longitudinal edges of the shank and having camming surfaces at the forward and rear edges thereof; a handle formed at one end with a flat shank-receiving socket defining an entrance passage of less width than the expanded shank and locking projection and laterally extended to form locking shoulders extending transversely outward from the opposite longitudinal edges of said passage near the inner end of the latter, the shank being compressible in the plane of the shank and blade for endwise insertion of the shank into the socket and expansible to snap the locking projection into yieldable locking engagement with either of said locking shoulders, the handle, shank and locking projection being formed to cooperate for the insertion and locking of the shank in transversely reversed positions and for the withdrawal of the shank by an outward pull upon the blade, and the handle cross section extending outward beyond the inserted locking projection in both of its locked positions to shield the locking projection from contact with the hand of the user of the knife.

3. A surgical knife comprising a blade integrally formed with a flat shank in the plane of the blade and longitudinally bifurcated to form two flexible and resilient fingers; a locking projection integrally formed on one 115 of said fingers at a point materially spaced from the blade and projecting transversely outward from one of the outer longitudinal edges of the finger and having camming surfaces at the forward and rear edges thereof; a handle formed at one end with a flat shank-receiving socket defining an entrance passage of less width than the expanded shank and locking projection and laterally extended near the inner end thereof to form locking 120 shoulders extending transversely outward from the opposite longitudinal edges of said passage, the shank fingers being compressible toward each other in the plane of the shank and blade for endwise insertion of the shank 125 130

into the socket and expandable to snap the locking projection into releasable locking engagement with either of said locking shoulders, the handle, shank and locking projection being formed to cooperate for the insertion and locking of the shank in transversely reversed positions.

4. A surgical knife blade of stamped sheet metal of uniform thickness and having parallel side faces and integrally formed with a flat shank in the plane of the blade, said shank being longitudinally bifurcated to form two flexible and resilient fingers, the blade and the fingers being of the same thickness; a locking projection formed on the outer longitudinal edge of one of the fingers at a point near the free end of said finger and projecting transversely outward and lying in the same plane as the fingers and having camming surfaces at the forward and rear edges thereof; and shoulders on the two edges of the blade at the juncture of the fingers with the body of the blade, said bifurcation extending inward to a point adjacent said shoulders to thereby render the shank compressible edgewise throughout substantially its entire length.

In testimony whereof I hereunto affix my signature.
